UNITED STATES PATENT OFFICE.

WILBUR F. SAWYER, OF NEW YORK, N. Y.

ADJUSTABLE HAT-BLOCK.

1,128,530.

Specification of Letters Patent. Patented Feb. 16, 1915.

Application filed March 23, 1914. Serial No. 826,649.

To all whom it may concern:

Be it known that I, WILBUR F. SAWYER, a citizen of the United States, and a resident of Brooklyn, city and State of New York, 5 have invented a certain new and useful Improvement in Adjustable Hat-Blocks, of which the following is a specification.

The invention relates to devices used in manufacturing hats and more particularly 10 to hat blocks or forms.

The objects of the invention are set forth hereinafter and in part will be obvious and they are attained and realized through the combinations and instrumentalities set forth 15 in the accompanying claims.

The invention consists in the novel articles, parts, structures, combination and improvements herein shown and described.

The accompanying drawings referred to 20 herein and forming a part hereof, illustrate one embodiment of the invention and together with the description serve to illustrate the principles thereof.

Of the drawings: Figure 1 is a side elevation of a device constructed according to 25 the principles of the invention; Fig. 2 is a top plan of Fig. 1; and Fig. 3 is a central section on line A—B of Fig. 2.

Referring by way of example to the drawings, a hat body 1 comprises a plurality of 30 separable members which together constitute the form upon which the hat is made. Said members are relatively movable with respect to each other, being separable from and approachable to each other, and by their relative movement and varying degrees or 35 amounts of separation or nearness, and the consequent change or adjustment in size, constituting a hat block or form upon 40 which hats of the different sizes can be made. Thus one of my hat blocks takes the place of a complete set of ordinary blocks, which set would comprise a separate hat block for each size of hat. As embodied, 45 said hat block 1 comprises two such separable and relatively movable members 2 and 3. Said members 2 and 3, in the embodied form, are divided transversely or midway through the block, and each of said members 50 comprises a portion of the hat body part 4 and also a portion of the brim forming part 5.

In practically applying the device, a suitable support is provided for the relatively

movable hat body parts, together with 55 means for indicating the relative position of such parts for hats of each given size. There are also provided means for holding the relatively movable or adjustable hat body parts in the position for any particular or 60 desired size of hat. When the members 2 and 3 are properly positioned for a desired size of hat, and the holding means are utilized to hold them in such position, any desired number of hats of such size can be 65 made. The device may then be very easily and quickly set for another desired size of hat through the agency of the indicating means. Said hat body members may be held in such position until the desired number 70 of hats of this particular size is made and so with all the different sizes of hats.

The support or bed 6 in the embodied form extends beneath and also to one side from the hat block proper, and is channeled longitudinally and centrally beneath the hat block and out to the edge of such sidewise extension as indicated at 7. In 75 said channel 7 lies a bar 8, longitudinally reciprocable in the channel 7 and having its 80 end projecting beyond the end of the bed 6, said projecting part serving as a handle. The hat body member 2 is fixed to the bed 6, and the body member 3 is fixed to the 85 slideable bar 8. Thus, when the bar 8 is 90 grasped by its handle and moved the member 3 is moved toward or away from the member 2 to change the size of the block for different sizes of hats, as previously explained.

In the embodied indicating means, a plate 9 is fixed to bed 6, and the plate 9 extends over the channel 7 and the bar 8. The plate 9 has at proper locations thereon and extending lengthwise of the bar 8 therebelow 95 marks and figures corresponding to the different sizes of hats. In the plate 9 at said marks are a corresponding series of perforations 10 extending therethrough. In the bar 8 is a hole 15 adapted to pass into 100 alinement or registry successively with the holes 10 in the plate 9 as the bar 8 is slid in or out. A pin 11 is set in the hole corresponding to the size of hat desired and as the hole 10 comes into alinement therewith, the 105 pin 11 drops into the hole 10, thus holding the hat block at the desired size until a new size is required. On the brim forming part

one or more measure or size indications 13 may be made of such form or kind as may be desired.

14 is a guide projection extending from 5 part 2 into a recess in part 3.

By my invention in a single device, each 10 workman has a block adapted to make every size hat, thus obviating the cost and room and storage of a whole set of the usual hat blocks and avoiding as well the trouble of handling a large number of such old hat blocks and the trouble of changing from one to the other. Other objects and advantages will be obvious or will be ascertained 15 from practice.

The invention is not limited to the precise form shown and described, but variations therefrom may be made, within the scope of the accompanying claims, without departing 20 from the principles of the invention and without sacrificing its chief advantages.

What I claim as my invention and desire to secure by Letters Patent, is as follows:—

1. A hat blocking device including in combination a hat block comprising a plurality of relatively movable hat forming members, a supporting base upon which said hat forming members are mounted, said base also extending out from said hat block, a bar 30 slidably mounted upon and slideable along said extension of said hat block, said bar being connected to one of said hat forming members of said hat block.

2. A hat blocking device including in combination a hat block comprising a plurality of relatively movable hat forming members, a supporting base to which one of said hat forming members is fixed and upon which base another of said hat forming members 40 is slideable, said base extending out from said hat block, a bar slidably mounted in said base and attached to one of said hat forming members.

3. A hat blocking device including in combination a hat block comprising a plurality of relatively movable hat forming members, a supporting base to which one of said hat forming members is fixed, said base extending out from said hat block, a bar slidably

mounted in said base and attached to one of 50 said hat forming members and size indicating means coöperating with said bar.

4. A hat blocking device including in combination a hat block comprising a plurality of hat forming members including a freely 55 moving member, a base to which one of said hat forming members is fixed, said base extending out from said hat block, a member slidably guided along said base and fixed to said freely moving hat forming member, and means for holding said slideable member and said freely moving hat member in position for a particular size of hat.

5. A hat blocking device including in combination a hat block comprising a plurality of hat forming members including a freely 65 moving member, a base to which one of said hat forming members is fixed, said base extending out from said hat block, a member slidably guided along said base and fixed 70 to said freely moving hat forming member, and means for holding said slideable member and said freely moving hat member in position for a particular size of hat and size indicating means coöperating with said holding 75 means.

6. A hat blocking device including in combination a portable hat block comprising a plurality of hat forming members, including a movable member for varying the size of 80 the hats to be made, a base for said hat block and extending outwardly therefrom, said base being adapted to rest directly on a table or like support, and means for varying the distance between said hat forming members, 85 means for holding said members in the various desired positions for making hats of various sizes, said distance varying means and said holding means being carried upon the upper part of said base.

In testimony whereof, I have signed my name to this specification, in the presence of two subscribing witnesses.

WILBUR F. SAWYER.
